COMMERCIAL DISHWASHING MACHINE

David A. Meeker and Gerald B. Fox, Troy, Ohio, % The
Hobart Manufacturing Company, 711 Penn Ave., Troy,
Ohio

Filed Aug. 25, 1964, Ser. No. 81,436

Term of patent 14 years

(Cl. D49—1)

FIG. 1 is a perspective view of a commercial dishwashing machine showing our new design with the doors in closed position; and

FIG. 2 is a perspective view of the machine shown in FIG. 1, with the doors in open position.

The dominant features of our design reside in the portions shown in full lines. The control arm for operating the door members of the disclosed dishwashing machine is substantially square in outline and is continuous around the machine except as indicated in FIGS. 1 and 2. The outside surfaces (not shown) of the side and rear walls have substantially the same appearance as the front and side doors shown.

The machine is particularly adapted for corner installation in normal use, and the rear of the machine, not normally visible, is therefore not an important feature of our design.

This application is a continuation-in-part of our copending application Serial No. 68,240 filed January 9, 1962, now Patent No. D. 199,196, granted September 22, 1964.

We claim:

The ornamental design for a commercial dishwashing machine, as shown and described.
